JOHN T. LAGOIS, OF NEW YORK, N. Y.

CAN SIFTER-TOP.

1,144,213.

Specification of Letters Patent. Patented June 22, 1915.

Application filed July 29, 1914. Serial No. 853,868.

To all whom it may concern:

Be it known that I, JOHN T. LAGOIS, a subject of the King of Great Britain, and a resident of the city of New York, borough of Brooklyn, in the county of Kings and State of New York, have invented a new and Improved Can Sifter-Top, of which the following is a full, clear, and exact description.

This invention relates to can sifter tops and has to deal more particularly with the valve for opening and closing the apertures in the can top through which the contents of the can is sifted.

The invention has for its general objects to improve and simplify the construction of can sifter tops so as to be reliable and efficient in use, comparatively simple and inexpensive to manufacture and so designed that there will be no loss or waste of the contents of the can in shipment or handling in the trade.

A further object of the invention is the provision of a simple, novel and effective valve which is prevented from accidentally opening during commercial handling or shipment of the can, but which can be easily and quickly opened or closed by the user.

With such objects in view, and others which will appear as the description proceeds, the invention comprises various novel features of construction and arrangement of parts which will be set forth with particularity in the following description and claims appended hereto.

In the accompanying drawing which illustrates one embodiment of the invention, and wherein similar characters of reference indicate corresponding parts in all the views, Figure 1 is a perspective view of the upper portion of a sifter can; Fig. 2 is a vertical section on the line 2--2, Fig. 1, showing the valve in closed position; Fig. 3 is a similar view showing the valve open; Fig. 4 is a perspective view of the valve removed; and Fig. 5 is a transverse vertical section on the line 5--5, Fig. 1.

Referring to the drawing, A designates an ordinary can body to the brim 1 of which is slipped on a cover 2 which is of usual form and has sifting openings or apertures 3 at one end and an aperture 4 in the side wall. The valve B is in the form of a plate 5 which slides in contact with the under side of the cover, as shown in Fig. 2, this plate having a stem or shank 6 which extends out of the opening 4 in the cover and terminates in a

grip 7. The plate 5 has side flanges 8 which extend downwardly at right-angles to the plane of the plate 5 and are disposed between the brim 1 and the side flanges 9 of the cover 2, so that the plate 5 is slidably supported by the body of the can. The plate 5 also has an end flange 10 which is disposed within the body of the can, and consequently the flanges 8 and 10 are separated by recesses 11 at the corners of the plate 5. The flange 10 bears against the inner surface of the brim 1 of the can body so as to assist in sealing the can and preventing the contents from passing out between the valve and cover and through the openings 3 in case the can is inverted or upset. As shown in Fig. 1, the label C is applied to the can body and also to the cover so that the cover cannot be detached, and this label covers the grip 7, which is shown by dotted lines in Fig. 1, so that in order to use the can the label is torn at the grip 7, so that the latter can be engaged and bent upwardly if desired, for enabling it to be more firmly taken between the finger and thumb for the purpose of pulling the valve out to open position, as shown in Fig. 3. When the valve is open the can is inverted so that the contents can be sifted out. In closing the valve it is merely necessary to push the bar 6 inwardly from the position shown in Fig. 3 to that shown in Fig. 2, and consequently the valve will remain in closed position by the frictional engagement thereof with the cover and frame of the can body.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. The combination of a body, a cover having a peripheral flange embracing the body and provided within its margins with sifting apertures, a plate-like valve disposed within the cover and having lateral

flanges which extend outside of the body and lie between the sides of the body and the flanges of the cover, whereby the valve is 5 slidable between the under side of the cover and the top edges of the body at opposite sides, and means connected with the valve for operating the same.

2. The combination of a body, a can cover having sifting apertures provided with a 10 peripheral flange embracing the brim of the body, a valve within the cover, said valve consisting of a flat plate having side flanges

engaging the outside of the brim of the body and the inside of the marginal flange of the cover, and a shank connected with the plate 15 and extending out of the cover to form a grip for operating the valve.

In testimony whereof I have signed my name to this specification in the presence of two subscribing witnesses.

JOHN T. LAGOIS.
